SAFETY VALVE VENTING SYSTEM FOR
DIPHENYLAMINE PROCESS

George L. Wiesner, Bound Brook, N.J., assignor to American Cyanamid Company, New York, N.Y., a corporation of Maine

Filed Sept. 18, 1956, Ser. No. 610,558

1 Claim. (Cl. 260—576)

This invention relates to method and apparatus for safety venting in processes in which a liquid chemical is processed under conditions of heat and pressure. More particularly, the invention relates to a venting system in the vapor phase deamination of aniline to diphenylamine, which throughout the specification will be referred to by its industrial abbreviation, DPA.

Processes which are operated at elevated temperatures or high pressures or both require safety valves to prevent explosion of the equipment when undue pressures are developed. In many cases it is feasible to vent the safety valve to the atmosphere usually through a short stack through the roof of the building in which the reaction equipment is housed. If, however, the vapors are dangerous, either because they are inflammable and so constitute a fire hazard or because they are toxic, or both, this method of venting a safety valve is not satisfactory. The loss of product when a safety valve blows may also be substantial. The vapor phase deamination of aniline to DPA is a typical instance of a chemical reaction such as is described above as the vapors are both inflammable and toxic. Therefore, the invention will be described in greater detail in conjunction with the vapor phase DPA process, although, of course, it will be obvious that what is said is equally applicable to any other chemical reaction which presents the same conditions.

In the vapor phase deamination of aniline to DPA, liquid aniline is maintained in a feed tank which, in conventional plants, is usually a large one, having a capacity of many thousands of gallons. From this tank aniline is pumped through preheaters and superheaters and brought up to a temperature of nearly 500° C. and usually a pressure which may run from 30 p.s.i. to 150 p.s.i. The hot compressed vapors then pass through tubular converters containing the deamination catalyst, the out gases are condensed and the DPA separated out and the unreacted aniline recycled. Because the conversion to DPA per pass is small, of the order of magnitude of a few percent, there is a very large recirculating load of aniline.

Normally a plant uses several converters in parallel as the catalyst has to be regenerated from time to time. Each converter and superheater require protection by standard safety valves, which are calibrated to relieve at a predetermined pressure. The aniline vapors which are released if a safety valve blows are quite inflammable and are also toxic so that the venting problem is a very serious one. It has been proposed to lead the vents from the safety valves to a high stack. This is extremely expensive and, unless the stack is hundreds of feet high, the problem of a toxicity hazard still remains because under unfavorable weather conditions small concentrations of the vented aniline and DPA vapors may sink to the ground, and aniline is toxic in very low concentrations if inhaled for a considerable period of time. Of course, when a safety valve blows into the stack, all of the aniline and DPA vented is lost, which is an added cost factor.

The present invention avoids any danger from fire or

2

toxicity and, at the same time, prevents any loss of product when a safety valve blows. The invention will be described in greater detail in conjunction with the drawing in which:

5 The figure is an elevation in diagrammatic form of a system using the present invention.

In the drawing one of a number of DPA converters is shown at 1 with a safety valve at 2 venting into a line 3 into which the safety valve from other converters, superheaters, etc., are also led. The aniline feed tank 5 is a large size and is designed so that in normal operation it cannot be emptied. This is effected by locating the aniline feed pumps 6, of which two are shown, with intakes well above the bottom of the tank. Cleaning out of the tank 15 can only be effected deliberately under authority of suitable supervisory personnel through a locked valved drain pipe 7. The tank has a short vent stack 8 which is designed to take care of very small amounts of vapor which may be given off from the aniline at ordinary atmospheric 20 temperatures. The line 3 is led to the bottom of the tank where it terminates in a perforated sparger pipe 4 which functions as a gas diffuser. This pipe is submerged well below the surface in a relatively large volume of aniline. In a tank of commercial size, this minimum capacity may 25 be of the order of 5,000 gallons or even more.

When a safety valve blows, the hot vapors of aniline, DPA and small amounts of ammonia which are generated in the reaction flow through the line 3 into the sparger pipe 4 where they are distributed as fine bubbles into 30 the cold aniline. Hot aniline vapors are immediately condensed and any DPA present is condensed and dissolved, and not lost, as it is pumped again through the cycle and recovered at its normal point. The stack 8 is sufficient to carry the small amounts of ammonia present 35 outside of the building in which the tank is located so that no acute toxicity problem is presented. The ammonia vapors, of course, are lighter than air and so disperse almost immediately.

40 Th present invention is applicable to any processes in which a liquid is fed. The only limitations are that the bulk of the gases which would be expelled through a safety valve are condensable and are not violently chemically reactive with the feed liquid. In cases where two or 45 more liquids are fed into a reaction, the venting can be distributed through the feed tanks or restricted to the one where the optimum condensing conditions prevail.

I claim:

50 In combination with a process system for the vapor phase deamination of aniline to diphenylamine which includes the steps of introducing liquid aniline into said system as the feed thereto; heating and vaporizing the aniline; in a closed reactor under pressures of from about 30 to about 150 p.s.i., contacting resultant aniline vapor with a deamination catalyst at elevated temperatures, 55 whereby a vapor mixture is produced comprising aniline vapor, diphenylamine vapor and ammonia gas; withdrawing as product a flow of said vapor mixture from said reactor and from the system; and also intermittently discharging additional portions of said vapor mixture from 60 said reactor through a separate safety vent means; the method of treating said intermittently discharged portions which comprises the steps of; (1) establishing in a separate enclosed vessel (a) a volume of liquid phase mixture comprising liquid aniline and (b) thereabove a vapor phase 65 mixture in equilibrium therewith; (a) withdrawing a flow of said liquid phase mixture from said volume; (3) introducing the so-withdrawn flow into said system as said feed thereto; (4) collecting all said intermittently discharged additional portions of vapor mixture; (5) discharging all so-collected vapor mixture throughout said 70 volume of liquid phase mixture at a level below the

surface thereof and in the form of fine bubbles, whereby aniline and diphenylamine in the so-discharged vapor mixture is condensed and the condensate remains in said volume of liquid phase mixture and the ammonia in said so-discharged vapor enters said vapor phase mixture thereabove; (6) removing resultant vapor phase mixture containing ammonia from said enclosed vessel; (7) adding liquid aniline from another source to said volume of mixture; and (8) maintaining the temperature of said added liquid aniline and the rate at which it is added to 10 said volume of liquid phase mixture at values such that

both the volume and the temperature of said volume of liquid phase mixture remain substantially constant.
